UNITED STATES PATENT OFFICE.

FRANK E. WILCOX, OF MECHANICSBURG, PENNSYLVANIA, ASSIGNOR OF ONE-HALF TO LESTER E. HICKOK, OF SAME PLACE.

DESIGN FOR A VEHICLE-CLIP.

SPECIFICATION forming part of Design No. 34,575, dated May 28, 1901.

Application filed April 26, 1901. Serial No. 57,632. Term of patent 14 years.

To all whom it may concern:

Be it known that I, FRANK E. WILCOX, a citizen of the United States, residing at Mechanicsburg, in the county of Cumberland and State of Pennsylvania, have invented and produced a new and original Design for Vehicle-Clips; and I do declare the following to be a full, clear, and exact description of the same, reference being had to the accompanying drawings, forming a part thereof.

Figure 1 is a view in perspective of the entire clip, showing my new design. Fig. 2 is a sectional view.

As shown by the figures of the drawings, the leading or characteristic feature of my design consists in the concavo-convex body portion having on one side a depending leg and on the other side two parallel depending legs and a perforated lug.

A is the body portion, which has a convex surface extending from B to B and a concave surface extending from C to C. On one side the body portion gradually tapers downwardly and takes the shape of a bolt end which is circular in cross-section and constitutes a depending leg D. On the opposite side of the body portion depend two parallel

legs E E, which terminate in bolt-shaped ends circular in cross-section. From the top and side of the body portion projects a perforated lug F, which lies in a plane parallel with the plane of the two legs E E. At the upper end of the lug is a tubular projection G, the axis of which coincides with the axis of the perforation through the lug.

The complete clip appears to the eye as an integral structure having a body portion concavo-convex in shape with three depending legs and a perforated projecting lug extending from the top and one side of the said body portion and in a plane parallel with the two parallel depending legs.

Having described my invention, what I claim as new, and desire to secure by Letters Patent, is—

The design for a vehicle-clip, as herewith shown and described.

In testimony whereof I affix my signature in presence of two witnesses.

FRANK E. WILCOX.
